CURTAIN AND DRAPE SUPPORT

Joseph M. Davis, Tacoma, Wash.

Application November 7, 1949, Serial No. 125,885

4 Claims. (Cl. 211—123)

1

My invention pertains to supports for curtains and drapes, and relates particularly to the novel construction of a collapsible support which is readily adapted for use with windows of diverse dimensions and arrangements.

It is a principal object of my invention to provide a curtain and drape support so constructed that when in use the curtains may be removed from or placed on the support without disturbing the drapes.

It is another important object of my invention to provide a curtain and drape support which, when applied to a large window, permits putting on or removing a single curtain at a time without disturbing the other curtains on the support.

It is a further object of my invention to provide a curtain and drape support which is collapsible to small compass for convenient handling and which is capable of assembly with a minimum of effort and time.

Another important object of my invention is the provision of a collapsible curtain and drape support which is extensible and adjustable whereby to accommodate installation upon windows of various shapes and sizes.

A further important object of my invention is to provide a collapsible curtain and drape support which is adapted for use with corner windows of various sizes.

These and other objects and advantages of my invention will appear from the following detailed description taken in connection with the accompanying drawing, in which:

Fig. 1 is a fragmentary plan view of a curtain and drape support embodying the features of my invention showing the same applied to a double window;

Fig. 2 is a fragmentary plan view showing a curtain and drape support of my invention applied to a single window, parts of said support being broken away to show details of construction;

Fig. 3 is a fragmentary plan view of a curtain and drape support embodying the features of my invention and showing the same applied to a corner window, parts of said support being broken away to disclose details of construction;

Fig. 4 is a fragmentary sectional view taken along the line 4—4 in Fig. 1; and

Fig. 5 is a fragmentary plan view of a modified form of connecting means for use on the structure shown in Fig. 3.

The curtain and drape supports embodying the features of my invention as illustrated in

2

the accompanying drawing are characterized generally by being formed of a plurality of elements proportioned and arranged in such manner as to be detachable one from another.

This arrangement is made possible by means of complementary plug-and-socket attachments and cup shaped brackets as described in detail hereinafter.

Referring particularly to Fig. 1 of the drawing, the curtain and drape support illustrated therein is constructed for use with a double window, i. e. a pair of windows which are separated laterally by a section of wall or other supporting structure. The curtain and drape support includes a pair of drape rods, preferably tubular, each of which is formed angularly, as by being bent adjacent one of its ends to form a substantially L-shaped member. In this manner, each drape rod is provided with a relatively short support arm 1, 1a which carries the weight of the assembly and a relatively long guide arm 2, 2a which serves as a guide and support for the drape. The support arm of each of the rods is fastened to the wall by suitable attaching means such as the recessed socket members 3, 3a mounted in the wall structure 4.

A similar socket 5 is provided in the wall or other structure separating the two windows. A bracket member or support arm 6 detachably secured in the socket 5 projects outwardly from the latter a distance substantially equal to the length of the support arms 1, 1a of the drape rods. Pins 7 project laterally from adjacent the end of bracket 6 and are proportioned and arranged to be received within recesses 7a in the rods at the ends of the guide arms 2, 2a. The drape rods thus are supported in a horizontal plane by means of the sockets 3, 3a and the pins 7.

Secured to the support arms 1, 1a of the drape rods and extending inwardly toward the center bracket 6 are the cup-shaped brackets 8, 8a. These brackets are positioned intermediate the ends of the support arms and are proportioned to form a seat for one end of each of the curtain rods 9, 10. Pins or short bars 11 extending laterally from bracket 6 in alignment with the brackets 8, 8a are adapted to be inserted in the opposite tubular ends 11a of the rods 9, 10.

In this manner the curtain rods are arranged detachably and in properly spaced parallel relation with the guide arms 2, 2a of the drape rods.

The structural arrangement of the curtain and drape support illustrated in Fig. 2 is de-

signed for use on a single window and differs from the assembly shown in Fig. 1 in the absence of the center bracket. Sockets 12, 12a mounted in the wall structure 13 adjacent the window receive the ends of the support arms 14, 14a of the drape rod. The arms 14, 14a may be connected through a single length of rod if desired, although it is preferred that the rod be severed, as shown, to accommodate adjustment in the length of the assembly. This adjustment is provided by means of a bar 15 which telescopes within a recess 15a in the drape rods adjacent the abutting ends of the aligned guide rods 16, 17.

A cup-shaped bracket 18 is secured to the support arm 14 while a pin 19 is provided on the opposite support arm 14a. The bracket 18 and pin 19 are positioned intermediate the ends of the support arms and extend inwardly toward each other. A curtain rod 20 extends between the bracket 18 and pin 19, being secured detachably thereto in the manner previously explained, i. e. one end of the curtain rod is supported on bracket 18 and the opposite recessed end 20a is telescoped over pin 19.

Referring now to Fig. 3 of the drawing, the curtain and drape support for a corner window installation illustrated therein includes a pair of drape rods 21, 22 bent to provide support arms 23, 23a and guide arms 24, 24a. The guide arm 24a of rod 21 may be of greater length than arm 24 of rod 22, to accommodate the proportionate window dimensions. The support arms 23, 23a of both rods 21, 22 are secured detachably in tubular sockets 25, 25a mounted in the wall 26 as explained hereinbefore. The terminal end of the guide arm 24a of rod 21 is similarly secured in socket 27. The terminal end of the guide arm 24 of rod 22 is received detachably in the cup-shaped bracket 28 extending laterally from the arm 24a of rod 21.

Cup-shaped brackets 29, 29a secured intermediate the ends of the support arms 23, 23a of rods 21, 22 extend in a direction parallel with the guide arms 24, 24a of these rods. A pair of curtain rods 30, 31 are supported at one of their respective ends in said brackets 29, 29a and extend therefrom in spaced parallel relation with the guide arms of drape rods 21, 22, respectively. The terminal ends of curtain rods 30, 31 are joined together adjustably by means of the L-shaped bar 32 which telescopes within a recess 32a in the end of each rod. Bar 32 may extend through a longitudinal slot 32b formed transversely through the guide arm 24a of rod 21 between the terminal end in socket 27 and the cup-shaped bracket 28. Alternatively, it may be formed in two sections each of which is attached substantially opposite the other to the guide arm 24a. In this manner the curtain rods 30, 31 may be adjusted to proper position and supported in proper elevation with respect to the drape rods 21, 22.

Means for securing the curtain rods 30, 31 adjustably in position with respect to the drape rods is illustrated in Fig. 5 of the drawing. In this arrangement, the cup-shaped bracket 29 of Figure 3 is replaced by a collar 33 which is mounted, by means of its central opening 38, for sliding movement on support arm 23. Pin 34 extending laterally from the collar 33 is adapted to be inserted in a recess 39 of the curtain rod 31. A similar collar 35, having a similar central opening 40, is mounted for sliding movement on the guide arm 24a of drape rod 21 between the bracket 28 and the socket 27. Pin 36 extending from

collar 35 enters a recess 41 in curtain rod 31 at the end opposite pin 34. One end of bar 37 is secured to collar 35 while its opposite end telescopes within a recess in curtain rod 30, as previously described. In this manner curtain rod 31 may be adjusted to variously spaced positions with respect to the guide arm 24 of drape rod 22.

It will be apparent to those skilled in the art that the coupling means illustrated in Fig. 5 may be substituted for the cup-shaped sockets and pins shown in Figs. 1, 2 and 3 if it is desired to provide means for adjusting the parallel spacing between the drape and curtain rods, respectively. Other modifications, such as the use of telescoping sections for the curtain and drape rods to accommodate greater variations in the length of the assembly, may be made as desired without departing from the scope and spirit of my invention.

Hence it will be apparent that by the present invention I have provided a combination curtain and drape support from which the curtain may be removed without disturbing the drape. This is accomplished simply by lifting one end of the curtain rod out of the cup-shaped bracket in which it is contained, and removing the other end of the rod from the pin over which it has been inserted. The curtain then may be removed from or replaced on the curtain rod which then may be placed on the support, again without disturbing the drape. In addition, where the support is used over a series of two or more windows, as in Figure 1, the curtains for each window may be handled individually without disturbing the curtains on the other window. Still further, the curtain and drape supports of the present invention are universally applicable to all of the usual situations in which such devices are used, i. e. over single windows, over multiple windows, and in corner installations. No matter what the application, they may be assembled rapidly and without the use of special tools.

Having now described my invention and the manner in which the same may be used, what I claim as new and desire to secure by Letters Patent is:

1. A curtain and drape support comprising a pair of substantially L-shaped rods each forming a support arm and a drape guide arm, means for interconnecting the guide arms, bracket means mounted intermediate the ends of each support arm and extending in the direction of the corresponding guide arm, a pair of curtain rods each proportioned and arranged to be mounted detachably at one of its ends on one of said support arm brackets and to extend in spaced relation with said guide arms, and bar means telescopically interconnecting the free adjacent ends of said curtain rods.

2. A curtain and drape support comprising a pair of spaced support arms, a pair of transverse drape rods each connected at one of its ends to one of the support arms and having a recess in the other of its ends, cup-shaped brackets mounted one intermediate the ends of each of the support arms and extending in the direction of the drape rods, a third support arm having thereon a first pair of oppositely extending pins and a second pair of oppositely extending pins, a pair of curtain rods each having a recess in one of its ends, the recessed ends being adapted to telescope over the said first pair of pins and to be supported thereby, and the opposite ends being adapted to be supported by the said cup-shaped brackets, the recesses in the drape rods being

adapted to telescope over the said second pair of oppositely extending pins.

3. A curtain and drape support comprising a pair of substantially L-shaped rods each forming a support arm and a guide arm, bracket means extending laterally from one of said guide arms for mounting the end of the other guide arm detachably therein, bracket means mounted intermediate the ends of each support arm and extending in the direction of the corresponding guide arm, a pair of rods proportioned and arranged to be mounted detachably at one of their respective ends on said support arm brackets and to extend in spaced parallel relation with said guide arms, and a substantially L-shaped member mounted on one of the guide means and telescopically engaging the adjacent ends of said second pair of rods.

4. A curtain and drape support comprising the combination of a pair of substantially L-shaped rods each forming a support arm and a guide arm, bracket means extending laterally from one of said guide arms for mounting the end of the other guide arm detachably therein, bracket means one of which is slidably mounted intermediate the ends of one support arm and extending in the direction of the corresponding guide arm, a pair of rods each of which is proportioned

and arranged to be detachably connected at one of its ends to one of said support arm brackets and to extend in spaced parallel relation with one of said guide arms, and a substantially L-shaped member slidably mounted on one of the guide arms and telescopically engaging the adjacent ends of said second pair of rods.
